F. B. WILDMAN.

KNITTING MACHINE.

APPLICATION FILED NOV. 12, 1908.

1,071,979.

Patented Sept. 2, 1913.

UNITED STATES PATENT OFFICE.

FRANK B. WILDMAN, OF NORRISTOWN, PENNSYLVANIA.

KNITTING-MACHINE.

1,071,979.

Specification of Letters Patent.

Patented Sept. 2, 1913.

Application filed November 12, 1908. Serial No. 462,317.

To all whom it may concern:

Be it known that I, FRANK B. WILDMAN, citizen of the United States, residing at Norristown, Pennsylvania, have invented 5 certain new and useful Improvements in Knitting-Machines, of which the following is a specification.

My invention relates to means for making loose courses in the fabric for the purpose 10 of transferring, and my object is to insure certainty of operation, prevent rupture or undue strain of the yarn, while at the same time rendering it possible to increase the length of the loops of the loose course.

15 In carrying out my invention I adjust the needle dial vertically when the loose course is to be formed and I prefer to effect this adjustment of the dial simultaneously with the adjustment of the drawing down cam 20 of the cylinder needles, and through connections forming an extension of the operating devices of the said needle cam.

25 My invention consists in the features and combination and arrangement of parts hereinafter described and particularly pointed out in the claims.

30 In the accompanying drawings—Figure 1 is a side view of the invention; Fig. 2 is a plan view of a detail part; Fig. 3 is a side view of a modification.

35 In these drawings the needle cylinder is indicated at 1, and the dial at 2. The latter is supported by the post or stem 3 extending up through the cross piece 4 of the knitting head, wherein it is held by the nut 5 on the screw threaded portion 6, of the said stem. The construction thus far described is well known in the art, it being the practice to adjust the needle dial vertically by 40 turning the nut 5, thus raising or lowering the post or stem 3 as the case is required, this turning of the nut being effected by hand.

45 In carrying out my present invention the stem or post carrying the dial is raised and lowered automatically through pattern controlled means. I prefer to accomplish this automatic control through connections leading from the same devices which control the 50 drawing down cam of the cylinder needles for making the loose course. These devices are well known but will be briefly described. They consist of the incline 7 connected by a post 8, with the drawing-down cam 9. The 55 post together with the cam is forced down at the proper moment by a screw 10 adjust-

ably mounted in an arm 11 pinned to a rock shaft 12, journaled in the cam cylinder 13. The rock shaft is turned one way by an arm 14 thereon being pressed upon by a disk or wheel 15 on a shaft 16. This shaft is movable vertically, being controlled by pattern means in a well known manner not shown, so as to be either in line with said arm 14 or with the arm 17 on a supplemental rock shaft 18 also journaled in the cam cylinder. These rock shafts are geared together in a known manner as indicated by the gearing at 19, 20, and when one arm, say that marked 14, strikes the wheel 15 the 70 rock shaft 12 will be turned so as to cause the screw 10 to engage the inclined head 7 of the post 8 and depress the cam 9 for making the loops of the loose course. When the disk or wheel 15 is lowered into the plane 75 of the arm 17 the said arm will strike the disk, turn the shaft 18 and through the gearing 20, 19 the rock shaft 12 will be returned to normal position, thus withdrawing the incline 7 and allowing the cam 9 80 to rise, to proceed with the regular courses.

It is to be understood that the disk or wheel 15 is simply moved vertically into the plane of first one and then the other of the arms 14, 17. This disk or wheel is fixed 85 relatively, however, to the rotary movement of the knitting head and this rotary movement brings the arms around to strike the disk or wheel when it is adjusted into the proper plane.

90 As above stated, my present invention concerns the automatic adjustment vertically of the needle dial in order to form the loose courses and this adjustment is effected through the rock shaft 12, which, as shown, 95 is extended vertically and is provided at its upper end with an arm 21 connected by a link 22 to an arm 23 extending from a cam 24 encircling the post or stem 3. The inclined surface 25 of this cam co-operates 100 with the incline 26 on the boss 27 of the cross piece 4. The stem of the post 6 is splined as at 27 to this boss so that while permitted vertical movement it is prevented from having rotary movement. The nut 5 105 is secured rigidly to the stem 3 by a set screw 28. When now the rock shaft 12 is operated the cam 24, by the connection described, will be turned and its incline will ride up the incline of the boss 27, and as 110 the said cam on its upper side engages the under side of the nut 5 it will raise the said

nut together with the post or stem 6 and thus raise the needle dial for the formation of the long loops of the loose courses and this action will take place simultaneously with 5 the depression of the incline 7 and the drawing-down cam of the cylinder needles. It will be understood that the cam 24 is provided with two inclines located diametrically opposite to each other, one of these being indicated in dotted lines.

The effect of the adjustment of the needle dial for making loose courses will be well understood by those skilled in the art, it being possible thereby to form loops of 15 maximum length without straining or rupturing the yarn.

I provide an adjustment for yarns of different gage and for this purpose the arm 23 of the cam 24 is provided with a slot 20 29 concentric to the center of the post 3 and this receives the screw or bolt which connects the said arm with the link 22. By loosening this screw or bolt the cam 24 may be set in different positions about the post 25 so as to secure greater or less lifting effects from the same amount of movement of the rock shaft 12.

It will also be understood that the needle dial may be accurately adjusted by hand 30 in its relation to the needle cylinder by loosening the set screw 28 and turning the nut 5, which working on the screw thread 6 will raise or lower the needle dial and having determined the proper position the set 35 screw 28 will be turned to fix the parts and then the automatic adjustment vertically may take place as above described.

I do not wish to limit myself to the precise construction and arrangement of parts 40 described, as other means may be employed for accomplishing the same result. For instance as shown in Fig. 3 to cam 24^x may co-operate with a collar 30 surrounding the

post 3, said collar having a screw 31 adjustable vertically therethrough and in relation to the cam incline 25^x, a jam nut 32 being employed to hold the screw in adjusted position. By adjusting the screw vertically more or less lifting effect will be secured in connection with the incline 25^x. 50 This collar is keyed to the post 3 and the post is held against rotation in the manner above described.

I do not wish to limit myself to the simultaneous operation of the stitch changing devices and the adjustment of the needle dial, as the cylinder cam may be operated slightly in advance of the dial.

I claim as my invention:—

1. In combination with the dial a cylinder, the drawing-down cam, means for operating the said cam automatically for producing the loose courses and means for simultaneously adjusting the needle dial for producing said loose course, said cam operating means and dial adjusting means being interconnected substantially as described.

2. In combination in a rib knitting machine, an adjustable draw-down cam for the cylinder needles, a cam for lifting the dial 70 post, a rock shaft connected with the said lifting cam, said rock shaft extending vertically from the cam carrier of the cylinder cam, an arm on said rock shaft for adjusting the draw-down cam of the cylinder, an arm 75 on said rock shaft to operate the same, a disk on the frame to contact with said arm, a second rock shaft geared to the first and an arm thereon to be operated by the disk, substantially as described.

In testimony whereof, I affix my signature in presence of two witnesses.

FRANK B. WILDMAN.
